CLAIM

The ornamental design for a cutter blade for an ophthalmic lens edger, as shown and described.

DESCRIPTION

FIG. 1 is a perspective view of a cutter blade for an ophthalmic lens edger, in accordance with the present invention;

FIG. 2 is a right side elevation view thereof;

FIG. 3 is a rear elevation view thereof;

FIG. 4 is a front elevation view thereof;

FIG. 5 is a left side elevation view thereof;

FIG. 6 is a top plan view thereof;

FIG. 7 is a bottom view thereof;

FIG. 8 is a perspective view thereof, shown in a condition of use; and,

FIG. 9 is a perspective view thereof, shown in a condition of use.

The broken lines in FIGS. 8 and 9 illustrate environmental structure that forms no part of the claimed design.

1 Claim, 8 Drawing Sheets
